MAGAZINE FOR AUTOMATIC FIREARMS

George Webb, Hartford, Conn., assignor to Colt's Patent Fire Arms Manufacturing Company, Hartford, Conn., a corporation of Connecticut

Original application March 22, 1940, Serial No. 325,405. Divided and this application April 6, 1942, Serial No. 437,850

4 Claims.

(Cl. 89—34)

The invention herein disclosed relates to a magazine for an automatic firearm and is a division of co-pending application, Serial No. 325,405, filed March 22, 1940, for an Automatic firearm. While not necessarily so limited, the invention is particularly applicable to an automatic firearm and/or feeder embodying some or all of the inventions disclosed in the following prior patents and application for patent.

J. M. Browning—1,525,065—February 3, 1925
 J. M. Browning—1,692,328—November 20, 1928
 C. Pfeiffer—1,692,277—November 20, 1928
 F. T. Moore—Ser. No. 305,240—November 20, 1939

The invention described herein relates to a magazine for holding an articulated-link cartridge feeder assembly in proper position to be fed to an automatic firearm such as disclosed in detail in said co-pending application, Serial No. 325,405. The invention not only relates to the magazine per se but also to the combination of the magazine and articulated-link feeder.

In the preferred embodiment of the invention, the magazine is adapted to accommodate an articulated-link cartridge feeder assembly with the assembly disposed in coil fashion to conserve space and produce a compact magazine. Means are also provided in the magazine to guide the feeder adjacent the exit portion of the magazine. Still further means are provided to maintain the leading end of the feeder in predetermined relationship with respect to the exit portion of the magazine.

A further feature of the invention relates to a loading plate for facilitating the introduction of an articulated-link cartridge feeder assembly into the magazine. The loading plate, in its preferred embodiment, is detachably secured to the magazine and is removable therefrom prior to attaching the magazine to the firearm.

The invention relates further to various other details of construction and combinations of parts which will be more fully apparent upon considering the following specification.

The firearm disclosed in said co-pending application, Serial No. 325,405, is so constructed that it can use either a rigid or an articulated-link cartridge feeder assembly, the use of one or the other depending upon the length of time sustained firing is desired. For short bursts of fire, a rigid feeder containing a small number of cartridges is sufficient. However, if a longer period of fire is desired, a magazine of the type comprising the instant invention is used in conjunction with an articulated-link cartridge feeder assem-

bly containing a greater number of cartridges than that contained in a rigid feeder.

When using a rigid feeder, a loading tray is detachably secured to the firearm adjacent the feed channel. When an articulated-link cartridge feeder assembly is used, the loading tray is removed and a magazine containing the articulated-link cartridge feeder assembly is detachably secured to the firearm by means similar to those used to secure the loading tray.

In the accompanying drawings I have shown in detail one embodiment of the invention and also certain variations thereof which have been found to be satisfactory. It will be understood, however, that without departing from the spirit of the invention there may be various changes in the construction and that the drawings are not to be construed as defining or limiting the scope of the invention, the claims forming a part of this specification being relied upon for that purpose.

In the drawings,

Fig. 1 is a side view of an automatic firearm embodying part of the invention, the forward portions of the barrel and recuperator being broken away.

Fig. 2 is a plan view of the firearm with the forward portion thereof broken away.

Fig. 3 is a rear view of the firearm.

Fig. 4 is a fragmentary plan view of the firearm showing the feed box with the cover plate removed and the magazine attached to the side of the feed box.

Fig. 5 is a fragmentary side elevation of a portion of the feed box showing the end of the feed channel and a feeder disposed in the feed channel in a position similar to that shown in Fig. 4.

Fig. 6 is a detailed plan view showing the feed slide, this view being partly in section.

Fig. 7 is a plan view of an articulated-link feeder adapted to be used in the magazine. This view is on a scale larger than that of Fig. 1 but smaller than Figs. 4 and 5.

Fig. 8 is a side view of the feeder shown in Fig. 7.

Fig. 9 is an end view of the feeder shown in Fig. 7.

Fig. 10 is a transverse vertical sectional view taken on the line 10—10 of Fig. 7.

Fig. 11 is a fragmentary longitudinal vertical sectional view taken along the line 11—11 of Fig. 7.

Fig. 12 is a view similar to Fig. 11 but showing the adjustment of the spring clip to accommodate a cartridge.

Fig. 13 is a view similar to Fig. 8 but showing the normal flexing of the feeder to conform to the requirements of a magazine.

Fig. 14 is a view similar to Fig. 8 but showing the possible reverse flexing of the feeder.

Fig. 15 is a view similar to Fig. 7 but showing an alternative feeder construction which may be used to provide end-to-end reversibility.

Fig. 16 is a plan view showing a magazine and a discharge chute adapted to use the articulated-link feeder shown in Figs. 7 through 15. In this view the firearm is indicated by dot-and-dash lines.

Fig. 17 is a rear elevational view of the magazine and discharge chute shown in Fig. 16.

Fig. 18 is a view showing the right side of the magazine as it appears when separated from the gun. Only the first cartridge and the front end of the feeder are shown in this view.

Fig. 19 is a fragmentary vertical sectional view taken on the line 19-19 of Fig. 16.

Fig. 20 is a fragmentary vertical sectional view taken along the line 20-20 of Fig. 16.

Fig. 21 is a plan view showing a loading plate associated with the magazine and also showing the relative position of the articulated-link feeder at the beginning of loading.

Fig. 22 is a fragmentary rear elevational view of the parts shown in Fig. 21.

Fig. 23 is a fragmentary plan view, with a certain portion broken away, of a manually operable feed mechanism adapted to be used in conjunction with the articulated-link feeder and the magazine shown in Figs. 7 to 22. This view is on the same scale as Figs. 4 and 5.

Fig. 24 is a fragmentary rear view of the manually operable feed mechanism shown in Fig. 23.

Fig. 25 is a fragmentary view, partly in elevation and partly in central longitudinal section, of the parts shown in Fig. 23.

Fig. 26 is a fragmentary plan view similar to Fig. 23 but showing the parts in different relative positions.

Fig. 27 is another fragmentary plan view similar to Fig. 23 but showing the parts in still different relative positions.

Fig. 28 is a fragmentary vertical transverse sectional view taken along the line 28-28 of Fig. 23. This view shows the articulated-link feeder in the position which it first occupies prior to being moved by the feed slide.

Fig. 29 is a view similar to Fig. 28 but showing the articulated-link feeder in the position which it occupies just prior to the feeding of the last cartridge.

The firearm or gun shown in the drawings is the same as disclosed in said co-pending application, Serial No. 325,405, and is otherwise generally similar to the firearms and/or feeders disclosed in the above-mentioned patents. For details not herein fully disclosed, reference may be had particularly to said co-pending application Serial No. 325,405 and any of the above-mentioned patents and application, of which Browning Patent 1,525,065 is among the more important.

The gun is well adapted for use in airplanes, although its use is not so limited.

In the drawings, particularly Figs. 1 through 3, the gun is shown in its horizontal position which may be regarded as "normal." However, the gun may be used at various angles of elevation or depression, or even inverted or it may be turned laterally. The terms "horizontal" and "vertical" as herein used are to be understood as relative

terms which are applicable when the firearm is in its normal position as shown. Furthermore, such descriptive terms as "front" and "rear" are to be considered in the sense that the end of the firearm from which the barrel or tube projects is the front end and the opposite end is the rear end. In the following description of the mechanism illustrated in the drawings, only sufficient description will be given of the various related parts of the mechanism and particularly the gun, to enable one to understand the construction and functions of the magazine, loading tray, magazine loading plate and the operation of the portions of the gun which coact to actuate the feeder to move the same from the magazine and through the feed channel. It is believed that a description of any other parts of the gun would be superfluous since a complete description of the operation of the gun per se is given in said co-pending application, Serial No. 325,405 to which attention is invited for a description of further details.

The present invention is mainly directed to a magazine adapted to be detachably secured to the feed box of a gun, the magazine being arranged to hold a plurality of cartridges or rounds of ammunition in a flexible feeder which is disposed in a spiral-like guideway in the magazine. Guide means for the cartridges are provided in the magazine to insure correct positioning of the cartridges at the delivery end of the magazine whereby they will be properly fed to the feed channel and will be engaged by a feed-slide reciprocably mounted within the feed box for transverse movement with respect to the longitudinal dimension of the feed box. The feed-slide is reciprocated by mechanism disposed within the feed box and the breech casing of the gun, said mechanism being the same as disclosed in said co-pending application, Serial No. 325,405, and to which attention is invited for details not described hereinafter.

The feed-slide which engages the feeder is so designed that it will move either a rigid or a flexible feeder through the feed channel of the feed box but this invention is mainly directed to a magazine adapted to accommodate a flexible feeder and therefore the main portion of the description of the feed-slide will deal with its actuation of a flexible feeder rather than a rigid feeder.

Details of the feeders, both rigid and flexible, are not claimed herein since the same form the subject matter of another application filed on even date herewith and also being a divisional application of said co-pending application, Serial No. 325,405.

In the drawings, and referring particularly to Figs. 1 through 3, the breech casing 2 has a barrel or tube 4 projecting from the forward end thereof. A feed box 6 is mounted on the upper side of the breech casing. The feed box 6 contains members of the cartridge feeding mechanism and is provided with a transverse channel 6^a into which the cartridges and the feed plate or feeder carrying the same may be fed from left to right. To permit access to the parts of the feed mechanism, the feed box 6 is provided with a movable top cover 12. The cover 12 is preferably entirely removable and, as shown, it has projecting longitudinal tongues 12^a, 12^b at its opposite edges which fit corresponding longitudinal grooves 6^b, 6^c in the side walls of the feed box, which grooves are shown in Fig. 4. Openings at 6^c, 6^e permit the cover to be moved vertically downward

to bring the tongues into register with the grooves. The cover is then moved rearward to enter the tongues in the grooves, and a spring latch 13 on the cover serves to hold it in place.

Detachably connected with the feed box 6 is a cartridge supporting device which is shown in Figs. 1 and 3 as being a shelf-like loading tray 14. As will be hereinafter made clear, a magazine may be substituted for the loading tray. When the tray 14 is used it serves to support a rigid cartridge feeder assembly preparatory to its insertion into the feed channel 6^a and into engagement with the feed mechanism. The tray 14 and the feed box 6 are provided respectively with connection devices which serve to connect them, but which permit them to be readily disconnected and separated. The connection devices may be varied as to details and as to relative arrangement of parts but, as shown, the tray 14 is provided with vertical walls 14^a and 14^b (Fig. 2) which are normally immediately adjacent the outer face of a bracket 15 on the left wall of the feed box, and the said walls are apertured to receive two pairs of studs 15^a, 15^b projecting from the said bracket 15. The studs 15^a, 15^b are notched at their bottoms and the tray 14 is provided with two spring-pressed latches 16, 16 (Fig. 3) each having two teeth 16^a, 16^b adapted to enter the notches in the studs to hold the tray in place. The two teeth are mounted on a vertical rod 16^b which is pressed upward by the spring. The latches 16, 16 are provided with buttons 17, 17 by means of which they can be pushed downward to permit disconnection and separation of the parts.

Referring particularly to Fig. 4 and also Figs. 28 and 29, the above-mentioned feed box 6 is preferably rectangular in form, having side walls 6^d and 6^e and front and rear walls 6^f and 6^g. The side walls 6^d and 6^e have depending portions which fit against and are secured to the corresponding side plates of the main breech casing 2. The feed box is normally closed at the top by the cover 12 which has already been described. Openings 6^h and 6ⁱ are provided respectively in the side walls 6^d and 6^e of the feed box to provide an entrance to and an exit from the above-mentioned transverse feed channel 6^a. The opening 6^h at the left side is of such size as to receive not only the feeder but also the cartridges, while the opening 6ⁱ at the right side need only be large enough to permit the exit of the feeder.

The feed channel 6^a (Fig. 1) is of such dimensions that it readily accommodates the feeder, either rigid or flexible, and permits the feeder to pass therethrough. For supporting and guiding the feeder and the cartridges as they enter and pass through the feed channel, there are provided two parallel guide plates or members 43, 43 which are provided with flanges 43^a, 43^b (Fig. 5) by which they are secured to the right-hand side of the feed box 6. These feeder guide members are so positioned that the main body portion 78 of the flexible feeder 14 with its parallel depending side flanges fits between them, thus enabling the guide structure 75^a of the feeder to rest upon the plates as shown in Fig. 5. The feeder assembly is thus supported and accurately guided. The guide members 43, 43 have downward facing cam surfaces 43^b (Figs. 28 and 29) which engage the cartridges to force or strip them downward out of engagement with the clips 80 when the feeder assembly is moved to carry each successive cartridge to or near a central position in the gun. Preferably the guide members 43, 43 have grooves

43^c, 43^d to provide clearance for the heads of the pivot pins and rivets 79 of the articulated-link feeder hereinafter described in more detail.

Two separate feed-slide guide members 44 and 45 (Fig. 4) extend transversely between the side walls of the feed box adjacent the openings 6^h and 6ⁱ and near the top of the box. Transversely movable in suitable grooves in the guide members is a feed slide 46. Referring particularly to Fig. 6, it will be observed that the feed slide 46 has longitudinal tongues 46^a and 46^b for fitting the grooves in the guide members 44 and 45.

Referring particularly to Figs. 6, 28 and 29, it will be seen that the feed-slide 46 carries a feed tooth adapted to successively engage the feeder assembly to effect feeding, and preferably there are two such teeth spaced apart in the direction of slide reciprocation by a distance approximately equal to the distance between two cartridges. The two teeth will engage the feeder assembly at the same time and they have other important advantages which will be hereinafter explained. When the feeder has feed slots such as 75^c, 76^c, 77^c the teeth engage these slots. The slide is so constructed and positioned that at the beginning of each feeding movement as shown in Figs. 28 and 29, the outer tooth 47^b is considerably outside the feed box and the inner tooth 48^b is inside the feed box.

As shown, particularly in Fig. 6, the two feed teeth on the slide 46 are formed as parts of two separate pawls 47 and 48 pivotally connected with the feed slide. In the feed slide 46 is a large central recess open at the bottom and partly closed at the top. The pawl 47 is generally rectangular in shape and is positioned in the recess in the slide, being mounted on a pivot pin 47^a. At the outer end of the pawl is a tooth 47^b adapted to successively enter the slots 76^c, 75^c, 77^c in the feeder. Depending from the top wall of the feed slide are two bosses 46^c, 46^d, these being within a large rectangular opening in the pawl 47. The second feed pawl 48 is pivotally connected at 48^a with the bosses 46^c, 46^d, and at its inner end is a tooth 48^b adapted to successively enter the feed slots 76^c, 75^c, 77^c of the feeder. It will be seen that the two pawls extend in opposite directions from their respective pivots and that they overlap each other. Separate springs 47^e and 48^e bias the respective pawls 47 and 48 to cause the teeth 47^b and 48^b to enter the said feed slots 76^c, 75^c, 77^c.

A manually operable means is provided for simultaneously withdrawing both of the teeth 47^b and 48^b from engagement with the feed slots of the feeder in order to permit the feeder to be withdrawn from the feed channel in retrograde direction. When there are two separate feed pawls they are moved simultaneously. As shown, the pawl 48 has two lateral projections 48^d, 48^e which overlie projections 47^d, 47^e on the pawl 47. The pawl 47 has a tail portion 47^e by means of which it may be moved to withdraw the tooth 47^b from the feeder, and when it is so moved the aforesaid projections move the pawl 48 to simultaneously withdraw the tooth 48^b. A button 49 (Figs. 28 and 29) is carried on the slide 45, this button having a stem 49^a which engages the tail portion 47^e of the pawl 47. Manual pressure on the button 49 will move both of the pawls 47 and 48 to withdraw the teeth 47^b and 48^b from the feeder.

Carried by the feed slide 46 is an actuating block 50 having depending lugs 50^a, 50^b, as shown in Fig. 4, which enter and fit notches 46^d, 46^e (Fig. 6) in the slide. A removable pin 50^b in

the block normally enters a hole in the slide to hold the block in place as shown in Figs. 4 and 29. During assembly, the slide is first put in place in the guides 44 and 45, and thereafter the block 50 is secured to the slide. The block 50, when connected with the slide, serves to hold the slide in place, the block engaging the side walls of the feed box to prevent removal of the slide. The block 50 provides a substantial body of metal for engagement by the feed lever 57, to be described, and it has an open-sided notch 50^c for receiving the lever. The above-mentioned button 49 for withdrawing the pawls is preferably carried by the block 50.

The block 50 preferably has an upward extending pin 50^d by means of which the block and slide can be moved independently of the breech mechanism as hereinafter explained in detail. When the pin 50^d is provided the cover 12 has an opening to provide clearance for the pin, there being an enclosing housing 12^b over the opening.

For operating the feed slide in timed relationship with the functioning of the firearm, mechanism is provided which mechanism is described and illustrated in said co-pending application, Serial No. 325,405. For purposes of the present invention, it is not believed that the present application need contain a repetition of the details of all of the operating mechanism since the instant application deals primarily with the construction of the feeder and magazine. However, the essential elements of said operating mechanism which are more directly connected to the feed slide will be described but, for details not set forth herein, attention is directed to said co-pending application.

As shown in Fig. 4, a bell crank 53 is pivoted at 53^a for movement about a vertical axis, the said lever being carried by bracket 54 secured to the walls of the feed box. The arm 53^b of the lever 53 which extends toward the right of the feed box is provided with a notch which receives a vertical cylindrical head 55 carried by a stud 55^a pivoted on the feed lever. The lower end of the feed lever is oscillated backward and forward in the breech casing and feed box by a suitable stud provided on the barrel extension which reciprocates longitudinally of the breech casing during the firing of the gun. Details of this mechanism will be found particularly in Figs. 5 and 8 of said co-pending application.

The arm 53^c of the bell crank lever 53 which extends forward is provided with a depending stud 56 which enters a slot at the rear end of connecting lever 57. This lever 57 is movable about a vertical axis at 57^a, being carried by a rearward extension 45^a of the transverse guide member 45. At the forward end of the lever 57 is a partly cylindrical head 57^b which enters a partly cylindrical portion of the notch 50^c in the block 50 on the feed slide 46.

The extension 45^a on the guide 45 carries a spring-pressed plunger 58 which engages a lug 57^c on the lever 57. By means of this plunger the lever 57 and the slide 46 and all of the movable parts connected with them are biased to the relative positions shown in Fig. 4. It will thus be seen that as the bell crank lever 53 oscillates about its pivot, the connecting lever 57 will be oscillated about its pivot to reciprocably move the feed slide 46 transversely of the longitudinal axis of the feed box to move the feeder within the feed channel. While the feed slide and associated parts are ordinarily returned by the biasing means 58, it should be ob-

served that, in any event, the connecting lever 57 would be returned to the position shown in Fig. 4 by the operating mechanism which is positively actuated by the movement of the barrel extension referred to above.

A carrier 60 is shown in plan view in Fig. 4, the carrier being mounted for movement about a horizontal axis. The main body 60^b of the carrier is located centrally between the side walls of the feed box and it is normally above the foremost cartridge being fed into the gun. Mechanism shown in detail in said co-pending application, Serial No. 325,405, actuates said carrier to move the forward end thereof vertically and, when moved vertically downward, the main body 60^b engages a cartridge which has just been stripped from the feeder by the cams 43^b and positively moves the cartridge into a position to be charged into the breech of the barrel by a charger provided in the chamber of the breech casing for this purpose, details of which are also described in said co-pending application, Serial No. 325,405.

The firearm is provided with suitable firing mechanism which need not be described in detail as it is similar to that in Browning Patent 1,525,065. For present purposes, it is sufficient to point out that this mechanism includes a trigger lever 66 adapted to effect firing when moved rearward with respect to the lock frame. If the trigger is held in its rearward position, continuous firing occurs automatically and, if released, firing ceases. For details of the firing mechanism attention is also directed to said co-pending application, Serial No. 325,405 and Browning Patent 1,525,065.

Prior to initial loading of the gun, the various parts of the gun (but not the feeder assembly) may be assumed to be in the relative positions shown in Fig. 4. When a rigid feeder loaded with cartridges is to be fired in the gun, the same is placed on the loading tray and then pushed manually into the feed channel while being guided by the guide members 43, 43. Where a flexible feeder is to be fed to the gun, a magazine, hereinafter described in detail, loaded with a flexible feeder containing cartridges, is secured to the side of the breech casing by the same means which secure the loading tray 14 thereto. When a magazine containing the flexible link loaded with cartridges is attached to the gun, a portion of the end link of the flexible feeder projects slightly beyond the exit of the magazine and the pawl-engaging aperture 76^c therein is adapted to be automatically engaged by the outer pawl 47^b of the feed slide when the magazine is attached and the feed slide is in the position shown in Fig. 4.

Particularly when a rigid feeder is being loaded into the feed channel 6^a of the gun, it is highly important that means be provided for preventing the feeder from being advanced too far. The necessity for preventing the feeder being advanced too far is due to the fact that when a rigid feeder is first introduced into the feed channel, it is pushed sufficiently far to have the forwardmost cartridge engage the cams 43^b to strip said cartridge from the feeder following which it will be disposed below the carrier 60^b and through movement of suitable mechanism will be lowered into position to be charged into the breech of the barrel by the charger. It is imperative that no other cartridge is introduced into the breech chamber until after said first cartridge has been fired and the empty shell has been extracted from the breech and ejected from the chamber in

order to prevent jamming of the gun. Without a suitable means for preventing it, the operator through carelessness or inadvertence might push the feeder so far as to release a second cartridge before the firing of the first, thus causing a serious jamming of the gun. One means for preventing manual overfeeding is disclosed in the above-mentioned application in the name of F. T. Moore, Serial No. 305,240.

For purposes of convenience, the feeder loaded with cartridges will hereinafter be referred to as the feeder assembly.

In accordance with the present invention a stop is provided which is normally operative to limit the movement of the feeder assembly in the feeding direction, particularly the initial manual movement thereof, and in association with the stop there is provided means for automatically moving the stop out of its operative position upon feeding movement of the slide so as to permit the slide to move the feeder assembly. Preferably the stop engages directly with the rigid or flexible feeder itself, although this may not be essential.

As shown particularly in Fig. 4, the feeder stop is a pawl 72 which is pivotally mounted at 72^a on the guide member 44, this pawl having a tooth 72^b which is adapted to engage the feeder. The pawl 72 is so positioned that its bottom face is immediately adjacent the top face of the front guide member 43. The pawl carries a spring-pressed plunger 72^c which biases it in the feeder-engaging direction. When the feeder is first advanced through the feed channel, the pawl 72 is moved out of the way of the feeder by the bevel 46^e on the feed slide and the tooth 72^b enters the first notch 75^b on the flexible feeder to positively prevent the operator from moving the feeder beyond the position shown in Fig. 4 when attaching the magazine to the gun. Normally this precaution does not have to be taken in the case of a flexible feeder inasmuch as the end of the feeder, when being loaded into the gun rarely projects beyond and the magazine exit no farther than the position shown in Figs. 16 and 17. Should a greater amount of the feeder project beyond the exit of the magazine however, the gun may not be jammed upon introducing the feeder into the feed channel when attaching the magazine to the gun due to stop 72 which functions in the manner just described. The tooth 72^b will engage the notch 76^b when the feeder has been advanced to the position shown in dotted lines in Fig. 28.

It will be particularly observed that the feeder, when engaged by the stop 72 as shown in Fig. 4, is so positioned that the second feed notch 75^c will be engaged by the inner feed pawl 48 upon the first feeding movement of the slide.

The mechanism for moving the stop 72 from the notches 75^b, 76^b comprises an upstanding lug 72^d formed on the pawl which lug is adapted to be engaged by the bevel 46^e on the feed slide when the feed slide is moved in the feeding direction. The parts are so related that the stop or pawl 72 is cammed forward by the bevel 46^e before the feed slide has moved far enough for the pawls 47 and 48 theron to engage the slots 75^c, 76^c of the feeder.

From the position shown in Fig. 4, the feed slide, after engaging the feeder, moves the feeder toward the right-hand or exit end of the feed channel a sufficient distance to release the next cartridge. Upon reaching this position, the feed slide is returned by connecting lever 57 to the

position shown in Fig. 4. On the return movement, the feed pawls are brought back to their proper positions for engaging the next following feed slots of the feeder. The feed slide goes through a distance slightly greater than the spacing between adjacent feed slots, this overtravel serving to insure proper engagement of the feed pawls with the feed slots even under the most adverse conditions.

Without special provision for preventing it, the feeder might be advanced farther than desired by the feeding movement of the feed slide by reason, for instance, of the inertia of the rapidly moving feeder and cartridges. In order to prevent any substantial or harmful over-travel of the feeder, following an automatic feeding movement, the tongue 46^a of the feed slide 46 is recessed at 46^f so as to permit the stop 72 to enter the next following notch 75^b. It will thus be seen that provisions are made for not only limiting the initial feeding movement of the feeder, but also for limiting each successive automatic feeding movement thereof.

Also mounted on the guide member 44 is a second pawl or retainer 73 somewhat similar to the pawl or stop 72. This pawl is pivoted at 73^a and it has a tooth 73^b adapted to enter the successive notches 75^b. A spring-pressed plunger 73^c serves to bias the pawl in the direction to engage the feeder. The tooth 73^b is beveled so as not to interfere with advance movement of the feeder but the tooth is adapted to enter one or another of the notches 75^b, 77^b to prevent any substantial retrograde movement of the feeder. Such retrograde movement might occur by reason of some accidental engagement of the feed slide while moving in retrograde direction with the feeder or by reason of an attempt by the operator to withdraw the magazine and feeder after entering it in the feed channel. As the result of the provision of the stop and the retainer, the feeder is held in such position that feeding will necessarily occur upon the next feeding movement of the feed slide.

Some retrograde movement of the feeder is possible when the feeder is advanced to the extreme position shown in Fig. 4, but not enough of such movement to interfere with normal feeding. With the feeder in the position to which it is normally moved by the feed slide at the end of the feeding movement, only a very little retrograde movement is possible. The stop and the retainer are spaced apart by a distance substantially greater than the normal feeding distance so that the retainer may be effective with the feeder in either of the two positions referred to.

The two pawls 72 and 73 are provided respectively with upstanding pins 72^e and 73^d by means of which the pawls can be withdrawn manually. If it is desired to remove the feeder toward the left prior to firing of all of the cartridges, this can be done by first moving the retainer pawl 73 forward by means of the pin 73^d and by lifting the pawls 47 and 48 by means of the button 49. If an incompletely filled feeder should be used, that is a feeder with the last one or more clips empty, it might be desirable to manually remove the feeder in the forward direction, that is, toward the right. This could be done by first pressing the stop pawl 72 forward by means of the pin 72^e, or it could be done by manually advancing the feed slide far enough to withdraw the pawl.

The flexible articulated-link feeder shown in Figs. 7 through 15 is designated in its entirety by

14. It comprises a number of intermediate links 75, a leading link 76 and a trailing link 77. Each of the links has a body portion 78 which is formed of sheet metal and bent to the shape of an inverted U as shown in Fig. 9. This is of the same size and shape as the main body portion of a rigid feeder. The depending side flanges of each body portion 78 are provided with notches or recesses 78^a for receiving a cartridge, each of the side flanges being thus provided with two spaced legs 78^b and 78^c. Two of the legs, as for instance the two legs 78^b, are offset so as to fit between the adjacent legs 78^c of the next adjacent link. The legs that thus overlap are joined by pivot pins or rivets 79, 79. The several connected body portions 78, 78 constitute the main body portion of the articulated-link feeder. Each of the links also has a spring clip 80 for holding a cartridge, this clip being similar to the spring clips provided on rigid feeders described in said co-pending application Serial No. 325,405.

As illustrated in Fig. 18 particularly, each cartridge has an annular groove 80^a provided in the projectile portion thereof. Each spring clip 80 is generally U-shaped as shown in Figs. 11 and 12 particularly and each leg of the U-shaped clip is provided with a slot or bifurcation 80^b to form a pair of resilient fingers on each leg of the spring clip. Each of said spring fingers is provided adjacent its outer end and near one edge with a struck-in portion or detent 80^c. When a cartridge is placed in the notches or recesses 78^a of the feeder, as shown in Fig. 18, the spring clip 80 engages the cartridge in such a way that a pair of oppositely disposed detents 80^c engage in the annular groove 80^a of the cartridge to not only releasably hold the cartridge within the feeder but also prevent movement of the cartridge with respect to the feeder in a direction substantially longitudinal of the cartridge. Since the detents 80^c are all mounted on separate resilient fingers and are thus independently movable, the other pair of opposed detents 80^c not engaged in the groove 80^a will positively engage the outer surface of the cartridge in a manner similar to that illustrated in Fig. 12 and thus positive contact is afforded between the cartridge and all of the resilient fingers provided on each spring clip 80.

The detents 80^c which may also be termed cartridge positioning means are so placed on the spring clip 80 that the cartridge may be reversed end-for-end in the feeder and one pair of oppositely disposed detents 80^c will always be in proper position to engage the annular groove 80^a of the cartridges to correctly hold each cartridge with respect to the feeder for reception in the feed channel of the feed box.

The particular form of spring clip formed with bifurcations 80^b may also be used in a feeder where, as in the case of the rigid feeders shown in said co-pending application, Serial No. 325,405, the edge of one of the notches 78^a engages the annular groove 80^a of each cartridge to restrain the cartridge against movement longitudinally thereof when held in the feeder. In the latter instance, the spring clip 80 merely holds the cartridge against movement in a direction transverse of the longitudinal axis of the cartridge. In such instance, however, if the spring clip 80 is formed with bifurcations 80^b as shown in Figs. 5, 9, 10, and 18, the provision of the detents 80^c will insure a plurality of contacts between each end of the U-shaped spring clip and the cartridge and thus provide more positive frictional engagement be-

tween the spring clip and the cartridge than in the case where a non-bifurcated spring is used and in which there is a possibility that only one point of contact may exist between each end of the spring and the outer cartridge surface.

Riveted or otherwise secured to the top of each U-shaped member 78 of each intermediate link 75 is a flat plate 75^a which has the same cross-sectional size and shape as the top plate of a rigid feeder. A somewhat similar plate 76^a is provided for the leading link 76 and a somewhat similar plate 77^a for the trailing link 77. The several separate plates 75^a, 76^a and 77^a are in alignment when the articulated-link feeder is straight and they constitute the top plate or guide structure of the feeder. The top plate 76^a of the leading link differs in that it is considerably longer to facilitate the entry of the feeder into the feed channel of the gun as will be more apparent from the description which follows. Preferably the top plate 76^a carries a legend giving instructions as to the relative positioning of the cartridges. The top plates 75^a and 76^a are notched at one side at 75^b, 76^b, the notches being similar to the notches on the side of a rigid feeder and being similarly spaced. The top plate 77^a of the trailing link has a notch 77^b which is open at the outer end. Each of the top plates 75^a, 76^a and 77^a together with the corresponding body portions 78, are transversely slotted at 75^c, 76^c and 77^c, the spacing between the slots being the same as the spacing between the slots of a rigid feeder.

The several plates 75^a, 76^a and 77^a are closely adjacent when the feeder is straight. The axes of the cartridges are at least as close to the plates as are the axes of the pivotal connections at 79, 79, and preferably the pivotal axes of the cartridges are closer to the plates than are the pivotal axes. This causes the cartridges, and incidentally the plates also, to separate when the feeder is normally flexed, as shown in Fig. 28, in order to accommodate itself to the magazine in which it may be entered. It will be obvious that if the relationship of the axes were reversed the cartridges would be brought closer together upon flexing, and this would necessitate an unnecessarily large spacing between the cartridges when the feeder is straight.

Preferably the plates, although closely adjacent, have narrow spaces between them which permit the feeder to flex to a small extent in the reverse direction as shown in Fig. 14. This reverse flexing is of assistance to the operator in loading the magazine, and it avoids any likelihood of injury to the feeder as the result of careless handling.

The articulated-link feeder as shown in Figs. 7 through 14 is not reversible, it being necessary to load the cartridges in a predetermined relation to the feeder in order that the feeder may properly function with the magazine and the gun. I may, however, provide a reversible articulated-link feeder as indicated by 81 in Fig. 15. This feeder is similar to the feeder 74, the intermediate links 82 being exactly like the links 75 except that the top plates 82^a have notches 82^b at both sides. Either one of the end links 83 may be the leading link or the trailing link. The top plate 83^a of each link 83 is of the same length as the top plate 76^a of the feeder 74, and it is provided at one side with a notch 83^b like the notch 76^b and is provided at the other side with a notch 83^c like a notch 77^b. The feeder 81 may be used with either end foremost.

The articulated-link feeder assembly is placed in a suitable magazine such as that which will now be described, the magazine holding it in a coiled position.

Figs. 17 through 20 show a cartridge-supporting device in the form of a magazine adapted to carry an articulated-link feeder. The magazine comprises two main front and rear plates 84 and 85 which are spaced apart and which are connected by longitudinal tie members 86, 87, 88 and 89. The two plates are also connected at the top by a horizontal flat plate 90 which is seated at its ends in slots in the plates. The front and rear plates 84 and 85 are provided respectively with brackets 84^a and 85^a which have vertical portions adapted to engage the outer face of the bracket 15 on the feed box. The brackets 84^a and 85^a have flat walls which are apertured to receive the same studs 15^a, 15^b which are used to hold the loading tray which has already been described. Carried by the brackets 84^a and 85^a are spring-pressed latches 91, 91, the same in construction as the spring-pressed latches 16, 16 of the loading tray. These latches are controlled by means of buttons 92, 92 which correspond to the buttons 17, 17 of the loading tray. It will be clear that the magazine can be put in place on the gun in the same position as the loading tray, the same studs 15^a, 15^b being utilized for holding it. Preferably the plates 84 and 85 are provided with lugs 84^b and 85^b which project toward the right to engage the casing of the gun and thus more rigidly support the magazine.

The rear face of the plate 84 and the front face of the plate 85 are respectively provided with helicoidal grooves 84^b and 85^b which are of the same shape and in longitudinal register with each other, these grooves being adapted to receive respectively the points and the heads of cartridges mounted in an articulated-link feeder such as the feeder 74 or 81 already described. In the particular magazine shown, the grooves in the plates are of sufficient length to accommodate 15 cartridges but it will be understood that the invention is not in any way limited to the particular number of cartridges shown.

Secured to the plate 90, at the bottom thereof, is a guide member 90^a having a T-slot 90^b therein to form a pair of channels adapted to receive and guide the plates 77^a, 75^a and 76^a constituting the guide structure of the feeder. The guide member 90^a projects at the right beyond the edge of the plate 90, as clearly shown in Figs. 16 and 17, and the slot 90^b is open at the top in this right hand projecting portion of the guide member. As is also shown in said figures, the left end of the slot 90^b is preferably flared both in plan and vertical elevational views to facilitate the entry of plates 77^a, 75^a and 76^a in said slots from the magazine. With the magazine in place, the guide means 90^a in the magazine and the guide means 43, 43 in the feed channel are in register with each other.

For carrying the magazine when it is separated from the gun, there is provided a handle 93 having pintles at its ends which are seated in bearing apertures in the plates 84 and 85. When the magazine is in place on the gun, the handle may

be in the position shown by the full lines in Figs. 16 and 17, but when the handle is to be used for carrying the magazine it is swung upward to the position shown in dot-and-dash lines in Fig. 17.

For convenience in loading the magazine, there is preferably provided a magazine loading plate

94 which is shown in Figs. 21 and 22. The plate 94 has upstanding end portions 94^a, 94^a which carry pins 94^b, 94^b which are similar to the pins 15^a, 15^a of the gun. This enables the loading plate 94 to be attached to the magazine and to be held by the same latches 91, 91 which normally serve to hold the magazine on the gun. The bottom of the loading plate 94 is so positioned that the loaded feeder is supported in exactly the proper position to enable the top plates of the feeder to readily enter the T-slot 90^b in the guide member 90^a of the magazine. In order to conveniently start the loading operation, the top plate of the trailing link of the feeder is placed in the open portion of the slot 90^b as shown in Fig. 21. The entire articulated-link feeder assembly is then pushed into the magazine, assuming a coiled position determined by the helicoidal grooves in the plates 84 and 85.

In order that the cartridges and the feeder may be accurately positioned in the magazine, there are provided two movable fingers 95 and 96 which are rigidly connected with a longitudinal pivot pin 97 seated at its ends in bearing apertures in the plates 84 and 85. The free ends of the fingers 95 and 96 project through suitable apertures 95^a and 96^a provided in the plate 90, Fig. 16. Springs 98, 98 serve to bias the pivot pin and the fingers for movement in the clockwise direction so as to tend to hold their end portions between the first two cartridges as shown in Fig. 17. This serves to accurately position the entire feeder assembly, that is the feeder and the cartridges, with the foremost engageable portion thereof in predetermined relationship with the magazine. With the construction shown the foremost engageable portion of the feeder assembly is the foremost feed slot, that is the slot 76^c in the leading link. This definite positioning of the feeder assembly is important for reasons which will presently appear.

The fingers 95 and 96 would interfere with the loading of the magazine if allowed to remain in their normal positions. In order that the fingers 95 and 96 may be conveniently withdrawn to permit loading, one of the fingers, as for instance 95, is provided with a tail portion 95^b which is adapted to be engaged by a pin 93^a on the handle 93. By moving the handle toward the right to the position shown by full lines in Figs. 21 and 22, the pin 93^a is brought into engagement with the tail portion 95^b of the finger so as to elevate both the fingers to the position shown by full lines in Fig. 22. This makes it possible for the entire feeder, with the cartridges therein, to be pushed into the magazine without any interference by the fingers 95 and 96. As soon as the feeder and the cartridges are in place, the handle is released and the fingers then move to the position shown by dotted lines in Fig. 22 and also shown in Fig. 17 so as to accurately position the cartridges and the feeder. The fingers 95 and 96 do not prevent withdrawal of the feeder and the cartridges from the magazine, but they do resist such withdrawal and they thus prevent any accidental movement of the feeder and cartridges out of the magazine during such handling as may be necessary prior to the placement of the magazine on the gun.

When a magazine and an articulated-link feeder are used, it is necessary or at least desirable, to provide a chute at the right side of the gun for receiving and guiding the empty portion of the feeder. A suitable chute for this purpose is shown at 99 in Figs. 16 and 17. For holding

the chute in place the right side of the feed box is provided with brackets 100, 100 which are apertured to receive pins 100^a adapted to extend through suitable holes in plates 99^a of the chute.

With an articulated-link feeder such as 74, mounted in a magazine secured to the side of the gun, there is no provision for engaging the feeder and the cartridges manually to advance them into the gun as is the practice with a rigid feeder. The forward end of the articulated-link feeder is in a position similar to that shown in Figs. 16 and 17, and the articulated-link feeder is advanced by a feeding action which is similar to that already described for the rigid feeder. However, there is no cartridge feeder assembly in the feed channel to cause the feed mechanism to operate automatically, and I therefore provide a special device for manually operating the feed slide independently of the breech mechanism of the gun to effect the initial advance of the feeder.

In Figs. 23 to 27 of the drawings, I have shown a suitable device for manually operating the feed slide independently of the breech mechanism. The barrel extension is in its forward position, and the slide itself and the levers 53 and 57 which normally operate it are entirely free to be moved manually.

The means for moving the feed slide manually may be widely varied as to location and as to construction, but the means shown is mounted on a special cover 101 adapted to be substituted for the before-described cover 12. The special cover 101 has tongues 101^a, 101^b corresponding to the tongues 12^a, 12^b for fitting the grooves 6^b, 6^b in the side walls of the feed box. The cover 101 is held in place by spring latches 102, 102.

The cover 101 has an opening 101^b therein through which projects the before-mentioned pin 50^d which is on the block 50 secured to the feed slide 46. Mounted on the cover 101 above the opening 101^b is a slide 103 longitudinally movable in guides 104, 104. Secured to the slide 103 and projecting upward therefrom is a handle 105 by means of which the slide may be manually movable. A coil compression spring 106 is interposed between a bracket 107 at the rear of the cover 101 and a bracket 108 on the slide 103. This spring is guided by a rod 109 which is secured to the bracket 107 and which has slidable engagement with the bracket 108. The rod 109 has a nut 109^a at its forward end which together with a washer constitutes a stop to limit forward movement of the slide. The spring is enclosed in a tube 110 which is secured to the bracket 107 and which is slotted at the bottom to provide clearance for the lower portion of the bracket 108.

The slide 103 has a raised portion 103^a which serves as a housing for a cam 111 adapted to engage the pin 50^d. The cam 111 has a portion 111^a rigidly secured to the slide and preferably also a portion 111^b which is pivoted to the slide at 111^c. A spring-pressed plunger 111^d tends to hold the cam portion 111^b in the relative position shown in Fig. 23.

When the slide 103 is manually moved rearward by means of the handle 105, the cam 111 engages the pin 50^d to move the feed slide toward the right, that is in the feeding direction. Fig. 26 shows the slide 103 moved rearward and it will be clear that continued rearward movement of the slide beyond the position shown in Fig. 26 will cause the cam 111 to release the pin. The pin and the slide then automatically move, as indicated by the arrows, back to the normal position at the left. When the handle 105 is re-

leased the slide 103 is returned in the forward direction by the spring 106 and the pin 50^d then pushes the portion 111^d of the cam toward the right to provide clearance. This construction makes it possible for the feed slide to instantly return to its normal position, without waiting for the return or forward movement of the slide 103. It will be seen that a single movement of the slide 103 rearward and again forward causes one complete feeding movement of the feed slide.

Fig. 28 is a view showing the magazine and discharge chute in place on the gun. The pins 15^a, 15^b (Figs. 4 and 23) on the feed box guide the magazine so that it moves horizontally into its final position. In so moving, the top plate 76^a of the leading link is entered in the space above the guide members 43, 43. The exact relative positioning of the feeder assembly as shown in Fig. 28 is insured by the engagement of the fingers 95 and 96 with the cartridges as already explained. With the feeder assembly in this position, the tooth on the feed pawl 47 is outside of the feed box and is entered in the foremost feed slot of the feeder, that is the slot 76^a in the leading link 76. Then by manipulating the slide 103 twice in the manner already described, the feeder can be advanced to the position shown by dot-and-dash lines in Fig. 28 thus effecting the loading of the first cartridge. It will be observed that the grooves 43^a, 43^b in the guide plates 43, 43 provide clearance for the heads of the rivets 79, 79 of the feeder.

With the first cartridge loaded as described, the operation of the gun takes place as before-described, when the trigger 68 is pulled. The fingers 95 and 96 of the magazine are cammed out of the way by the cartridges and do not interfere with the feeding action. The forward end portion of the feeder passes into the chute 99 and is guided downward as shown in Fig. 29.

It will be understood that during the operation of the gun the pawls 72 and 73 function with the articulated-link feeder in the same manner that they function with the rigid feeder. The only essential difference is that the articulated-link feeder does not have a bevel corresponding to the bevel 42^b on the rigid feeder 42 shown and described in Serial No. 325,405. This is unnecessary for the reason that the articulated-link feeder is advanced only by the action of the feed slide, and when the feeder is so advanced the feed slide itself moves the pawl 72 out of the way, no bevel on the feeder being necessary. The cam 46^a on the feed slide is of sufficient length to hold the stop pawl 72 out of engagement with the feeder at each movement thereof, until the joint between the top plates has moved beyond the pawl. This avoids any possibility of entry of the tooth 72^b of the pawl into the joint space, with resultant breaking or jamming.

It will be observed that the inner pawl 48 on the feed slide is not needed, and in fact is not used, for starting the feeding movement of the articulated-link feeder as shown in Fig. 28. After the first feeding step, the two pawls act simultaneously, but at the time of the feeding of the last cartridge the feeder has passed beyond the range of action of the pawl 47 as shown in Fig. 29. The feeding of the last cartridge is effected solely by the pawl 48. Thus both pawls are necessary, one for starting the feeding and the other for completing it.

Upon the feeding of the last cartridge, the stop pawl 72 will be entered in the open ended notch

11^b of the feeder, the feeder then being free to be withdrawn from the gun. Final withdrawal of the feeder may take place by gravity or if necessary by manual action.

What I claim is:

1. A firearm magazine constructed and arranged to contain a cartridge feeder assembly comprising a feeder and cartridges mounted therein, said magazine having an exit and comprising in combination, means defining a path of movement for said feeder assembly within said magazine, means adjacent the exit of the magazine constructed and arranged to normally engage a feeder assembly and position it with its leading end in a predetermined relation to the exit of the magazine and to prevent retrograde movement of said feeder assembly, a handle movably secured to the magazine for carrying the same, and means carried by said handle and movable thereby into engagement with said positioning means to move the same out of engagement with the feeder assembly, whereby movement of said feeder assembly in retrograde direction into the magazine may be effected as when the magazine is being loaded.

2. An automatic firearm magazine for use with an articulated-link cartridge feeder assembly, the said magazine having an exit and comprising in combination front and rear plates respectively provided in their rear and front faces with similarly shaped helicoidal grooves adapted respectively to receive and guide the front and rear ends of the cartridges, means adjacent the exit of the magazine for normally engaging the feeder assembly to position it with its leading end in a predetermined relation to the magazine and to prevent retrograde movement of said feeder assembly, a movable handle for carrying the magazine, and means carried by said handle and movable thereby into engagement with said positioning means to move the same out of engagement with the feeder assembly, whereby movement of said feeder assembly in retrograde direction into the magazine may be effected as when the magazine is being loaded.

3. An automatic firearm magazine for use with an articulated-link cartridge feeder assembly, the said magazine having an exit and comprising in combination front and rear plates respectively

provided in their rear and front faces with similarly shaped helicoidal grooves adapted respectively to receive and guide the front and rear ends of the cartridges, a pivot pin extending transversely between the front and rear plates, two movable fingers connected with the pivot pin and having portions disposed adjacent the exit of the magazine, said fingers being disposed respectively at the front and rear of the feeder guiding means and said portions thereof being adapted to normally engage certain cartridges to position the feeder assembly with its leading end in a predetermined relation to the exit of the magazine, means for biasing the pivot pin and the fingers in the direction to engage the fingers with the cartridges, a handle pivotally connected with the front and rear plates, and means on the magazine operable by movement of the handle out of its carrying position for moving the pivot pin and the fingers against their bias out of cartridge engaging position, whereby movement of said feeder assembly in retrograde direction into the magazine may be effected as when the magazine is being loaded.

4. A magazine adapted to be attached to an automatic firearm having a feed channel and reciprocable feed slide, said magazine having a feeder assembly exit and comprising in combination means adapted to slidably receive and hold a cartridge feeder assembly comprising a flexible feeder detachably holding cartridges, a carrying handle movably mounted on the magazine, means carried by the magazine adjacent its exit for normally engaging the feeder assembly to prevent retrograde movement thereof into the magazine and maintain the leading end thereof in a predetermined position for reception in said feed channel of the firearm when the magazine is attached thereto whereby said leading end of the feeder assembly may be engaged by the feed slide of the firearm and moved thereby in feeding direction into said feed channel, and means carried by said handle and movable thereby into engagement with said first-mentioned means to remove the same from engagement with said feeder assembly, whereby retrograde movement of the feeder assembly into the magazine may be effected as when the magazine is being loaded.

GEORGE WEBB.
